HOLDER FOR TAPS, DRILLS, AND THE LIKE

Leonard Nachemov, New York, N. Y., assignor to
 Abraham J. Sossner, Theodore S. Sossner, and
 Nettie Sossner, a copartnership doing business
 as Sossner Steel Stamps, New York, N. Y.

Application December 26, 1942, Serial No. 470,312

1 Claim.

(Cl. 29—89)

The present invention relates to holders for taps, drills and the like, and particularly to fixtures for use in machines used to mark sizes or other data or insignia on such tools or the like, or for performing other operations thereon.

The principal object of this invention is to provide a novel and improved device of the character mentioned, whereon, the articles to be worked on, are accurately and securely held and properly positioned, and adaptable by simple adjustment to accommodate articles of different sizes, to facilitate quantity production of the machine operation on different articles of the type set forth.

Another object hereof is to provide a novel and improved holder for all types of taps, drills and similar items, which is simple in construction, easy to use, and efficient in carrying out the purposes for which it is designed.

Other objects and advantages will become manifest as this disclosure proceeds.

In the accompanying drawing, forming part of this application, similar characters of reference indicate corresponding parts in all the views.

Fig. 1 is a plan view of a holding device following the teachings of this invention.

Fig. 2 is a side view thereof.

Fig. 3 shows a section taken at line 3—3 in Fig. 1.

Fig. 4 shows a fragmentary detail of Fig. 2, including a positioning arm used herein to maintain the mounted articles against axial rotation on center-mounting elements.

Fig. 5 is a fragmentary sectional detail showing the square end of the shank of one of the mounted articles, a tap in this instance, resting on a positioning arm.

Fig. 6 is a similar view, where said arm is provided with a groove wherein said tap end may rest.

Fig. 7 shows a modified form of a center-mounting element.

In the drawing, the numeral 15 designates generally a frame member comprising essentially a forward bar 16, from which there rearwardly extends the spaced bars 17. The numeral 18 designates generally another frame member comprising essentially a bar 19, from each end of which extends a member 20, each in contact with the outside surfaces of the bars 17, whereby frame 18 is slidably along frame 15; the bars 16 and 19, in the embodiment shown, being in constant parallel relation. The elements 20 are each provided with a slot 21, while

the bars 17 have a series of tapped holes 22, whereby the frame members can be secured by means of bolts 23 for instance, to maintain the bars 16 and 19 in any desired spaced relation.

5 The forward bar 16 carries a series of center-mounting elements comprising the pins 24 slidably mounted therethrough; said elements being preferably equi-spaced along said bar, and in parallel relation among themselves, and having pointed ends 24' extending from the rear of said bar 16, and headed ends 24'' extending forward of said bar. About each of the shanks of said pins 24 is a coil spring 25, between the rear surface of the bar 16 and the pointed-headed ends 15 24'.

The rear bar 19 carries a series of center-mounting elements, comprising the pointed pins 26, fixedly extending towards the pins 24, and respectively in alignment with them. The axes 20 of all pins 24 and 26 are co-planar. Said rear bar 19, along its underside, carries a circular rod 27, supported on spacer blocks 28 and 29 depending from said rear bar. A series of forwardly extending arm elements 30 have lateral 25 nipples 31 which are loosely carried on said circular rod 27; one arm 30 at every pin 26; said arms 30 being urged upward towards their respectively related pins 26, by means of the individual springs 32, which act in torsion. The 30 free forward ends of said arms 30 are a little forward of the pins 26 respectively, and in or near contact therewith, behind such forward ends of said arms. It is also desirable that each arm 30 be symmetrically positioned with respect to the axis of their related pins 26, respectively.

35 The center-mounting elements may be pointed as are 24' and 26, or provided with sockets as at 32, and the contact surface of the arm 30 may be other than flat, as for instance it may be provided with a V trough as at 33, or otherwise, all of which design will be determined by the nature and construction of the ends of the articles to be mounted between the pairs of aligned pins 24 and 26. The holder specifically 40 illustrated herein is adapted for mounting taps 34 thereon, for taps usually are provided at each end with a center-socket.

45 In use, the frames 15 and 18 are set and secured to each other so that the distance between 50 the opposite center-mounting elements 24 and 26 is a little less than the length of identical taps 34 to be mounted in the device. The taps 34 are individually mounted in the following manner: A particular end of the tap 34 is set 55 atop one arm 30, shifting the latter downwardly

against action of its spring 31, until the pin 26 over said arm enters the socket at that particular end of the tap 34, by a slight shift of said tap in the direction of said pin; the tap 34 being held tilted in hand. The aligned forward pin 24 is now pulled forwardly at 24'', against action of its spring 25. The other end of tap 34 is now moved by the hand which holds it, to lie in the line of said pair of pins 24 and 26. Thereupon, knob 24'' is released from hand and point 24' will enter the socket at this forward end of the tap 34, whereby said tap is mounted in axial alignment with said pins, and the arm member 30 will maintain the tap in axial fixation, because the particular cross section of the tap at either end is non-circular. After all the taps 34 are mounted as aforesaid, the fixture may then be mounted in required manner in or on any machine which is to perform some operation on the taps 34, as marking the sizes thereon.

The tie-bars 35 may be used to accurately position the fixture in the marking machine or the like. After the machine operation on the mounted taps 34 is completed, the manner of removal of the taps, and replacement by others for repetition of the machine operation, is obvious.

This invention is capable of numerous forms and various applications without departing from

the essential features herein disclosed. It is therefore intended and desired that the description herein and the phraseology and terminology employed herein is for purpose of explanation and not of limitation, and that the specific embodiment set forth shall be deemed illustrative and not restrictive, but that the patent shall cover all patentable novelty herein disclosed; reference being had to the following claim rather than to the description herein to indicate the scope of this invention.

I claim:

In a device of the character described, the combination of a frame, a pair of aligned, adjustably spaced center-mounting elements on the frame, adapted for mounting an article capable of axial rotary movement between them, a shaft mounted on said frame adjacent to and in transverse relation to one of said center-mounting elements, an arm pivotally mounted at one end on said shaft and a resilient means adapted to urge the free end of the arm towards said one center-mounting element, whereby said arm upon contact with the article, will maintain said article in any placed position and permit manual axial rotary movement of said article to other positions about said axis.

LEONARD NACHEMOV.
